PRINTING PRESS

Robert H. Hose, Summit, N.J., assignor, by mesne assignments, to Fairchild Camera and Instrument Corporation, a corporation of Delaware

Filed Apr. 5, 1962, Ser. No. 69,594

Term of patent 14 years

(Cl. D64—11)

Fig.1.

FIG. 1 is a front and right side perspective view of a printing press showing my new design.

FIG. 2 is a left side elevational view thereof with parts of the broken line disclosure being shown broken away for convenience of illustration; and

FIG. 3 is a rear elevational view thereof looking in the direction of the arrow 3-3 of FIG. 2.

The essential features of my design reside in the portions shown in solid lines on the drawing.

I claim:

The ornamental design for a printing press, as shown and described.
